Inventor:

Lyman Tobey
C. H. Watson & Co.

UNITED STATES PATENT OFFICE.

LYMAN TOBEY, OF NAPLES, NEW YORK.

WICK-TUBE FOR LAMP-BURNERS.

SPECIFICATION forming part of Letters Patent No. 278,295, dated May 22, 1883.

Application filed November 8, 1882. (No model.)

To all whom it may concern:

Be it known that I, LYMAN TOBEY, a citizen of the United States, residing at Naples, in the county of Ontario and State of New York, have 5 invented certain new and useful Improvements in Wick-Tubes for Lamp-Burners; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 This invention relates to an improved wick-tube for lamp-burners, by which an ordinary light may be turned down to a small round flame or taper without becoming extinguished, thus constituting a night-lamp; and the invention consists in providing the upper edge 20 of the wick-tube on each side with a notch or nick and turning the edges outward to form wings, as hereinafter more fully described and claimed.

25 The invention is illustrated in the annexed drawings, in which Figure 1 is a perspective view of my improved wick-tube, together with the attached parts, showing the appearance of the notched wick-tube before the edges of the same are turned outward. Figs. 2 and 3 are 30 side views, showing modifications. Fig. 4 is a perspective view of the upper part of a wick-tube embodying my invention, and showing the edges or sides of the notches or nicks turned out to form wings.

Like letters designate like parts.

In carrying my invention into effect I provide the upper edge of the flat wick-tube A on each side with a notch, a, that is located 40 centrally, as shown, and may be formed by cutting or filing in any suitable manner. It is

obvious that when the lighted wick is turned down the central portion of the wick between the oppositely-located notches a a will continue to burn after the flame at the outer edges 45 of the wick is extinguished. I thus get a small round flame or taper from an ordinary lamp-wick. The upper edge of the wick-tube may be straight across, as shown in Fig. 1, convex, as shown in Fig. 2, or concave, as shown 50 in Fig. 3, and the notch may be either rectangular, as shown in Fig. 1, or V-shaped, as shown in Figs. 2 and 3; or it may be of a rounded or other convenient outline. The edge of the wick-tube adjacent to the notches a a is bent outward 55 to form wings b b, as shown in Fig. 4; or the wings may be formed by simply nicking or slitting the wick-tube for a short distance and then turning the wings outward. This construction of wick-tube does not injure the tube for ordinary purposes when burning a full flame, but rather, by concentration of the flame at the center, it tends to obviate liability of breaking 60 the chimney. The wings or flanges b b serve as fenders to protect the flame and prevent 65 flickering when the wick is turned down to burn low, and they also add considerable to the volume of the flame when the wick is turned up.

Having thus described my invention, what I claim as new, and desire to secure by Letters Patent, is—

A wick-tube having its upper edges notched or slitted and provided with wings b b, substantially as shown and described.

In testimony whereof I affix my signature in presence of two witnesses.

LYMAN TOBEY.
